The ornamental design for a pin striped thin film solar module for street lamp, as shown and described.

DESCRIPTION

FIG. 1 shows a simplified perspective view of a pin striped thin film solar module for street lamp showing our new design according to a first embodiment of the invention.

FIG. 2 is a front side elevational view thereof.

FIG. 3 is left side elevational view thereof.

FIG. 4 is right side elevational view thereof.

FIG. 5 is a top plan view thereof; and,

FIG. 6 is a bottom angled view thereof.

The broken lines shown on the drawings depict portions of the fixture that form no part of the claimed design.
